UNITED STATES PATENT OFFICE.

JACOB HIRSCH, OF NEW YORK, N. Y., ASSIGNOR TO ROYAL LAMP SHADE CO., INC., OF NEW YORK, N. Y., A CORPORATION OF NEW YORK.

DESIGN FOR AN ARM FOR A BRIDGE LAMP OR THE LIKE.

Application filed June 20, 1927. Serial No. 22,506. Term of patent 3½ years.

To all whom it may concern:

Be it known that I, JACOB HIRSCH, a citizen of the United States, residing at the city, county, and State of New York, have invented a new, original, and ornamental Design for an Arm for a Bridge Lamp or the like, of which the following is a specification, reference being had to the accompanying drawing, forming part thereof.

Fig. 1 is a front view of an arm for a bridge lamp or the like showing my new design.

Fig. 2 is a side view of the same.

I claim:

The ornamental design for an arm for a bridge lamp or the like, as shown.

JACOB HIRSCH.
